UNITED STATES PATENT OFFICE

**HAROLD L. JOYCE, OF CHICAGO, ILLINOIS, ASSIGNOR TO JAS. P. MARSH & COMPANY,
OF CHICAGO, ILLINOIS, A CORPORATION OF ILLINOIS**

DESIGN FOR A RADIATOR AIR VENT

Application filed October 15, 1930. Serial No. 37,265. Term of patent 14 years.

To all whom it may concern:

Be it known that I, HAROLD L. JOYCE, a citizen of the United States, residing in Chicago, in the county of Cook and State of Illinois, have invented a new, original, and ornamental Design for a Radiator Air Vent, of which the following is a specification, reference being had to the accompanying drawings, forming a part thereof;

Figure 1 is a top plan view of the radiator air vent showing my design; and

Figure 2 is a view in elevation thereof.

I claim:

The ornamental design for a radiator air vent, substantially as shown.

HAROLD L. JOYCE.
